Primary Examiner — George D Kirschbaum*(74) Attorney, Agent, or Firm* — Malloy & Malloy, P.L.**CLAIM**

The ornamental design for a multi-directional signal assembly, as shown and described.

DESCRIPTION

FIG. 1 is a front view illustrating one embodiment of my design for a multi-directional signal assembly;

FIG. 2 is a rear view thereof;

FIG. 3 is a right side view thereof;

FIG. 4 is a left side view thereof;

FIG. 5 is a perspective view thereof;

FIG. 6 is a top plan view thereof; and,

FIG. 7 is a bottom plan view thereof.

The broken line showing of a post is included for the purpose of illustrating portions of the “article” and forms no part of the claimed design.
